UNITED STATES PATENT OFFICE.

WOLFGANG FELIN EWALD, OF BERLIN, GERMANY, ASSIGNOR TO GESELLSCHAFT FÜR DRAHTLOSE TELEGRAPHIE M. B. H., OF BERLIN, GERMANY, A CORPORATION OF GERMANY.

LOUD SPEAKER.

Application filed November 6, 1924, Serial No 748,007, and in Germany November 8, 1923.

The present patent application relates to a loudspeaking telephone which differs from the known arrangements in that, instead of the horn causing a distortion of tone and also disturbing extraneous noises, an arrangement is employed by which a natural reproduction of sound and good amplification is possible.

According to the invention the source of sound is arranged at the focus of a conoid or paraboloid produced by the rotation of a parabola round its axis, in such a way that the source of sound is mechanically countercoupled to the reflector of sound by means of a damping kind of suspension. In this way it is possible to attain a total reflection of the sound waves without influencing the character of sound, furthermore the usual horns which, up till now, have caused disturbing noises on account of their shape and the mechanical coupling with the source of sound are eliminated.

The annexed drawing shows an embodiment of the invention. A is a hollow body in the shape of a paraboloid of revolution on which the sound waves, starting from the focus F and issuing from the telephone T or another source of sound, fall. B and C are the holding arrangements for the source of sound T which is fastened to the reflector of sound A by means of damping substances D which, for instance may be made of some inelastic substance such as felt.

Spherical hollow bodies of not too large an aperture are similar in shape to the paraboloids of revolution and can therefore replace them.

Having described several embodiments of my invention, I am entitled to all other modifications as fall fairly within the scope of the following claims.

1. A loud speaking telephone receiver com-

prising a reflector structure having an interior surface in the form of a paraboloid, a sound producing device positioned substantially at a focus thereof, and inter-connecting supporting means therebetween comprising an inelastic material. 45

2. A loud speaking telephone receiver comprising a reflecting surface having a focus, a sound producing means positioned at said focus, and a mechanical coupling means therebetween adapted to absorb mechanical sound vibrations therefrom. 50

3. In combination a reflecting surface having a focal point, a supporting stand therefor, a sound producing means positioned at said focus, and a supporting means therefor, comprising a felt cushion. 55

4. A loud speaking telephone reproducer comprising a curved sound reflecting surface having a focus, a sound producer including a diaphragm, positioned substantially at said focus and adapted to radiate sound vibrations toward said reflecting surface, and supporting means therefor, comprising supporting arms and vibration absorbent members in combination. 60

5. A loud speaking telephone receiver comprising a curved sound conveying means, a sound producing means cooperating therewith and a mechanical coupling means therebetween adapted to absorb sound vibrations impressed upon the material thereof. 70

6. A loud speaking telephone receiver comprising a reflecting surface having a focus, a diaphragm positioned at the focus, and means for supporting the diaphragm consisting of an absorbent material fastened to the reflecting surface and a plurality of radial arms connecting the diaphragm to the absorbent material. 75
